UNITED STATES PATENT OFFICE.

WILLIAM A. SMITH, OF PHILLIPSBURG, NEW JERSEY, ASSIGNOR TO THE DENVER ROCK DRILL MANUFACTURING COMPANY, OF DENVER, COLORADO, A CORPORATION OF DELAWARE.

MOTOR.

1,401,003.

Specification of Letters Patent. Patented Dec. 20, 1921.

Application filed October 16, 1916, Serial No. 125,945. Renewed May 9, 1921. Serial No. 468,170.

To all whom it may concern:

Be it known that I, WILLIAM A. SMITH, a citizen of the United States, residing at Phillipsburg, in the county of Warren and State 5 of New Jersey, have invented certain new and useful Improvements in Motors, of which the following is a specification.

The present invention relates to motors operated by fluid under pressure, and more 10 particularly is of the valveless type.

It has been proposed in tools of this character to control the admission of motive fluid by necks extending from the piston head proper, and in certain instances these 15 necks have also performed the function of a hammer extension that delivers the blow to the tool, either directly, or through the interposition of a tappet. In one type in which a rear extension or neck has been employed, 20 the neck has constituted solely the motive fluid controlling means, and is not only inactive in receiving pressure from the motive fluid, but actually detracts from the power obtained because of the surface it occupies 25 at its juncture with the piston head, which surface is thus made idle. In the modern development of this type of tools, moreover, where rapid and relatively heavy blows are given, unless these necks are of material 30 thickness, they are apt to break off, so that their cross sectional area with respect to the piston head must be relatively great.

One of the primary objects of the present invention is to provide a construction 35 of this type, wherein the surface of the piston head occupied by the junction therewith of the neck and thus made inactive, is compensated for by an active surface provided upon the neck, and as a result, a sur- 40 face equal to the entire cross sectional area of the piston head is secured on the active or striking blow of the hammer.

An embodiment of the invention is illus- 45 trated in the accompanying drawings, wherein:—

Figure 1 is a longitudinal sectional view through a tool with the piston in one extreme position, and

Fig. 2 is a similar view with the piston 50 in the opposite extreme position.

Similar reference numerals designate cor- 55 responding parts in all the figures of the drawings.

In the embodiment illustrated, a cylinder 55 member is employed, comprising a body 3

having a rear head 4 and a front head 5, to which is connected a suitable tool holder or chuck 6, a dolly 7 being illustrated as the tool mounted in the holder or chuck. The cylinder body is provided with a bore 8 60 which may be termed a head chamber, the rear head being provided with a distinctive chamber 9 of smaller diameter, which may be considered a neck chamber. The front head 5 is also provided with a bore 10, 65 which I have also entitled a neck chamber.

Operating in the cylinder member is a piston consisting of a head 11 that reciprocates in the head chamber 8, a rearwardly extending neck 12 that operates in the neck 70 chamber 9, and a forwardly extending neck 13 that moves in the neck chamber 10. It will be understood that the parts 11, 12 and 13 preferably form a unitary or integral piston. It will be noted that the necks 12 75 and 13 are of the same diameter and length so that the piston can be reversed and either end used as the hammer extension. This materially lengthens the life of the piston.

The neck 12 has a reduced portion 14 con- 80 tiguous to its juncture with the head 11, and the neck 13 also has a reduced portion 15 also adjacent to the head 11. These two reduced portions 14 and 15 form in effect annular grooves or channels on opposite sides 85 of the piston head. The portions of the necks 12 and 13 directly adjacent to the head 11 are in the form of bosses 14^a and 15^a, which fit the inner ends of the neck cham- 90 bers 9 and 10 so as to substantially close the same and trap the motive fluid on oppo- site sides of the head 11 at the ends of its stroke, so as to produce cushions whenever the head for any reason makes a stroke the extreme length of the head chamber. Mo- 95 tive fluid supplied from any suitable source is conducted by suitable means, not shown, to a supply port 16, and from this supply port, oppositely extending channels 17 and 18 lead to annular grooves 19 and 20 formed respec- 100 tively in the heads 4 and 5 and surrounding the chambers 9 and 10. An exhaust port 21 opens into an intermediate portion of the head chamber 8, communicating with an internal annular groove 22 therein. Another 105 channel 23 extends from the rear end of the head chamber 8 to the front end of the neck chamber 9, the rear portion of said neck chamber being slightly enlarged in diameter,

as shown at 24.

110

- It is thought that the operation of the motor will be clear to those skilled in the art. When motive fluid is admitted through the port 16, if the piston is in the position shown 5 in Fig. 1, the fluid is cut off from the front end of the head chamber by the front end of the neck 13, but can flow through the channel 17, and groove 14 into the rear end of the head chamber 8 behind the piston 11.
- 10 The piston head being behind the exhaust port 21 and channel 22, the portion of the head chamber 8 in advance of the piston is open to the atmosphere, and consequently the piston will be driven forwardly to strike 15 its blow. In connection with this forward movement, it will be noted that the motive fluid which enters behind the piston head 11 will also flow through the channel 23 into the rear end of the neck chamber 9, and consequently against the rear end of said neck. Therefore the rear surface 25 of said neck and the rear surface 26 of the head are both 20 acted on simultaneously, and a pressure surface equal in extent to the entire cross sectional area of the piston head 11 is secured. As the piston advances, the rear end of the rear neck 12 will cut off communication between the channel 17 and the rear end of the head chamber 8, while the front channel 18 25 will be brought into communication with the front end of the head chamber 8 in advance of the piston 11 as seen in Fig. 2. The piston head 11 will also cross the groove 22 and exhaust port 21, so that now the motive fluid 30 will act against the front end of the piston head 11 and the motive fluid in rear of said head can exhaust freely. It will also be noted that the neck chamber 9 is also opened to the exhaust through the channel 23, so 35 that the pressure is entirely relieved not only against the rear surface 26 of the head 11, but also against the rear surface 25 of the neck 12.

With this construction therefore a heavy 40 striking blow can be secured, and the diameter of the neck 12 which controls the supply of motive fluid to the rear face of the head, may also be relatively great, inasmuch as the surface thus occupied by the 45 neck is compensated for by the surface at the rear end of the neck.

From the foregoing, it is thought that the construction, operation and many advantages of the herein described invention will 50 be apparent to those skilled in the art, without further description, and it will be understood that various changes in the size, shape, proportion and minor details of construction may be resorted to without departing 55 from the spirit or sacrificing any of the advantages of the invention.

Having thus fully described my invention, what I claim as new, and desire to secure by Letters Patent, is:—

65 1. In a motor of the character set forth,

the combination with a cylinder member having a head chamber and opposite neck chambers extending therefrom, said cylinder member having supply ports opening into the neck chambers, of a piston operating in the cylinder member and comprising a head in the head chamber and necks respectively operating in the neck chambers, said necks having reduced portions of less cross sectional area than the neck chambers 70 to alternately and intermittently afford communication between the ports and the head chamber on opposite sides of the head, and bosses at the juncture of the head and necks that substantially close the inner ends of 75 the neck chambers whenever the piston makes a stroke of extreme length, thereby forming cushions of trapped motive fluid.

2. In a motor of the character set forth, the combination with a cylinder member 80 having distinctive piston chambers, of a piston operating in the cylinder member and having different portions in the different chambers, said portions respectively having pressure surfaces faced in the same 85 direction, and means for directing motive fluid to one chamber against the surface therein and exhausting it therefrom, and a channel constituting means of communication between the rear portion of said chamber and the front portion of the other chamber, said latter chamber from the channel rearwardly having a diameter greater than that of the portion of the piston therein, permitting the supply to flow from the first 90 mentioned chamber to said other chamber in rear of the piston, and the exhaust to flow from said other chamber in rear of the piston to the first mentioned chamber.

3. In a motor of the character set forth, the combination with a cylinder member having a head chamber and a neck chamber, of a piston having a head operating in the head chamber, and a neck operating in the neck chamber, means for supplying motive 100 fluid to the head chamber to operate against said head, means for permitting the exhaust to escape from said head chamber, and a channel between the rear portion of the head chamber and the front portion of the 105 neck chamber, and said neck chamber from the channel rearwardly having an increased diameter that causes its walls to be spaced from the neck of the piston and said channel and enlarged diameter permitting the 110 entrance of motive fluid to the neck chamber in rear of the neck and its exhaust therefrom by way of the head chamber.

4. In a motor of the character set forth, the combination with a cylinder member 115 having a head chamber and a neck chamber having a reduced portion that communicates with the head chamber, of a piston having a head operating in the head chamber, and a neck operating in the neck cham- 120 ber, and a neck operating in the neck cham- 125 ber, and a neck operating in the neck cham- 130 ber, and a neck operating in the neck cham-

- ber, said neck fitting the reduced portion and being spaced from the walls of the portion in the rear thereof, means for supplying motive fluid to the head chamber through the reduced portion of the neck chamber to operate against said head, means for permitting the exhaust to escape from said head chamber, and a channel between the rear portion of the head chamber and the front enlarged portion of the neck chamber for permitting the entrance of motive fluid to the latter and thence to the rear end of the neck and its exhaust therefrom by way of the head chamber, said neck constituting means for controlling the supply of motive fluid to the head chamber and consequently to the neck chamber.
5. In a motor of the character set forth, the combination with a cylinder member having a head chamber and a neck chamber of less diameter extending rearwardly therefrom, of a piston having a head operating in the head chamber and a neck operating in the neck chamber, the front portion of the walls of the neck chamber snugly encircling the neck of the piston to prevent communication between the two chambers and the rear portion of the encircling walls of the
- neck chamber being spaced from said neck, and means for directing motive fluid to both the head and neck chambers to act against the rear faces of the head and neck.
6. In a motor of the character set forth, the combination with a cylinder member having a head chamber and a neck chamber of less diameter extending rearwardly therefrom, of a piston having a head operating in the head chamber and a neck operating in the neck chamber, the front portion of the walls of the neck chamber snugly encircling the neck of the piston to prevent communication between the two chambers and the rear portion of said neck chamber being enlarged, the encircling walls of said enlarged portion being spaced from said neck, and means for directing motive fluid to the head chamber and the enlarged portion of the neck chamber to act against the rear faces of the head and neck.
- In testimony whereof, I affix my signature in the presence of two witnesses.

WILLIAM A. SMITH.
